PRINTING MACHINE FOR PRINTING VARIABLE AREAS SIMULTANEOUSLY

Frederick Shurley, Windsor, Ontario, Canada, assignor to Guthrie Ceramic Labelling & Machinery Co., Inc., Dover, Del., a corporation of Delaware

Application July 11, 1938, Serial No. 218,691

29 Claims. (Cl. 101—124)

The invention relates to printing machines for printing variable areas simultaneously.

The present invention differs from my former Patents 2,060,385 and 2,085,126 by devising a mechanism which will automatically print two different designs of variable area simultaneously on the same article, whereas in the aforesaid patents, and in all other patents with which I am familiar, only a single design is applied to the article at one time. I accomplish this feature by providing a mechanism on the printing machine which imparts a differential rate of movement to the printing members which carry different areas in the design to be printed.

Selecting, but not limiting myself to a bottle, for example, it has been the custom to print a design on the body of the bottle, and then in a separate operation print a design on the neck of the bottle. The difficulty in printing on the body and neck of the bottle results from the fact that the periphery of the body of the bottle rotates at a greater rate of speed than the periphery of the neck. The circumference of the body of the average beer bottle is approximately eight inches, and the circumference of the neck is about four and one-half inches. This means that in order to simultaneously print on the body and neck of the bottle, the stencil or printing screen for the neck of the bottle should travel only four and one-half inches while the screen or stencil for printing the body of the bottle travels eight inches. In my present invention, I print on the larger and smaller area of the same article, in a very efficient, satisfactory and economical manner.

Another feature of the present invention is to devise a mechanism which performs all these functions automatically.

A further object of the invention is to print bands, marks, designs, objects, letters, or numerals in series or otherwise, or combinations of two or more of the foregoing elements in color on the bodies and reduced portions of bodies, such as bottles, which may be made of materials penetrable or impenetrable to the coloring materials.

With the foregoing and other objects in view, the invention consists of a novel combination, assembly, construction and arrangement of parts as will be hereinafter more particularly described and illustrated in the accompanying drawings, but it is to be understood that changes, variations, and modifications may be resorted to without departing from the invention in the claims.

In the drawings, wherein like reference char-

acters indicate like parts throughout the several views:

Fig. 1 is a top plan view of the machine of the invention partly broken away having the work carrying member removed, and showing the printing members at substantially one end of their oscillating path.

Fig. 2 is an end elevation of the machine partly broken away, and without the work carrying member.

Fig. 3 is a fragmentary vertical section taken substantially on lines 3—3 of Figure 4, and looking in the direction of the arrows, and leaving out the work carrying member.

Fig. 4 is a fragmentary side elevation looking at the side where the Geneva gear is located and having that side partly broken away.

Fig. 5 is a fragmentary longitudinal section through the upper part of the machine with the conveyors and work carrying member removed.

Fig. 6 is a fragmentary end elevation of the machine, at the opposite end from Figure 2.

Fig. 7 is a perspective view of the carriage of the auxiliary printing member removed from the machine.

Fig. 8 is a fragmentary side elevation of the machine in the area of the Geneva gear.

Fig. 9 is a section taken substantially on the plane of line 9—9 of Fig. 8.

Fig. 10 is a fragmentary vertical section through a portion of the support and the work carrying member showing the parts in printing position.

Fig. 11 is a diagrammatic sectional view showing the relation of certain of the parts in printing position.

Fig. 12 is a diagrammatic view showing the position of the chuck pins with relation to the cam on the work carrying member in the printing, discharge and charge position.

Fig. 13 is a fragmentary perspective view of the chuck pin engaged in the cam.

Referring to the drawings, it will be seen that the parts of the machine are mounted on a stationary support A composed of a pair of parallel inclined side beams 16, 17 secured to a pair of legs 18 near the middle, and another pair of legs 19 at the lower end of the beams. On each side of the support is a longitudinal brace 20 extending between the corresponding legs 18, 19 of each pair of legs. Depending from the ends of side beams are a pair of transversely spaced brackets 22 in the ends of which are journalled a shaft 23 to which is fixed the pair of idle sprocket wheels 24. About these sprocket wheels 25

- are trained one end of the pair of transversely spaced endless chains 25 which form the upper or discharge conveyor on which the articles are dropped, or deposited, from the work carrying member B to be later described in detail. The inner ends of the chains 25 are trained about driving sprockets 26 fixed on the drive shaft 27, which shaft turns the work carrying member B, and the drive shaft is journalled in bearings 28.
- 10 one bearing being anchored to each of the pair of supporting legs 18.
- The inner ends of a pair of outwardly extending arms 29 are secured to the legs 18, and in the outer free ends of the arms are journalled the 15 charging conveyor drive shaft 30. On intermediate portions of shaft 30, are a pair of spaced sprocket wheels 31 about which are trained respectively, one of a pair of spaced endless chains 32 which form the charging conveyor. On the 20 pairs of conveyor chains 25 and 32 are V-shaped flexible prongs 33 fixed to the links. The members 33 on one chain of the pairs, align with the members 33 on the other chain to form a transverse pocket or saddle to receive the articles to 25 be printed, which articles are shown in the drawings as bottles 34. Where articles other than bottles are to be printed, the prongs may be of various shapes to accommodate the shape of the article, and the space between the chains of each 30 pair may be regulated accordingly by adjusting the respective sprocket wheels for the respective pairs of chains by means of the set screws 35, as is more clearly shown in Figure 6. It will be seen that the drive shaft 30 is driven by a chain 36, one end of which is trained about the sprocket 37 on the end of the shaft, and the other end is trained about a sprocket 38 fixed on the outside of another sprocket 39. The sprocket 39 idles on a spindle 40 secured at its inner end to the 40 outside of the support A on one of the longitudinal braces 20. The other end of the chains 32 of the charging conveyor is trained about a pair of spaced sprockets 41 fixed to shaft 42 that is journalled in the legs 19.
- 45 On the one side brace 20 is anchored the prime mover, such as an electric motor 43, the drive shaft 44 of which is connected to the transmission gears mounted in gear casing 45, and extending from the gear casing is the drive shaft 46. One sprocket wheel 47 fixed to the drive shaft 46 on the inside, drives the sprocket 47' on the outer end of the crank shaft 48 by means of chain 49. Another sprocket wheel 50 on the outside, and fixed to the shaft 46, drives the work carrying member B by an endless chain 51 trained about the Geneva gear C on the outer end of shaft 27. The chain 51 passes over the spring pressed sprocket 52, and about idler sprocket 39 from which sprocket 39, on the lower or charging 55 conveyor receives its driving power as heretofore described.
- The crank shaft 48 is journalled in the ends of the side beams 16-17, and in the center is made with a bifurcated crank 53 between the arms of which the bearing collar 54 on the outer end of connecting rod 55 is journalled on the bolt 56 secured to the crank arms 53. The bolt 56 is slidable in slots in the arms 53 to adjust the throw of rod 55. On the terminal of crank shaft 70 48, outside of sprocket 47, is fixed a second crank arm 57 having a slot 58 which accommodates the adjustment of a bolt or crank pin 59 on which is mounted a ring bearing 60 on the connecting rod 61. As will presently appear, the difference 75 in throw in cranks 53 and 57, with other ex-

pedients, causes the printing members to have a differential movement so that variable areas will be printed simultaneously on the same article, such as the bottles 34.

For the purpose of illustration, I have shown two printing members D and E, with which are associated respectively a scraping member F and G. As will presently appear, the printing members vibrate or oscillate in a normally rectilinear path and the scraping members sweep coloring material over the printing surface on both the outward and return stroke of each vibration or oscillation. The coloring material passes through the parts of the printing surface that are pervious to the coloring material and the coloring material passing through the pervious parts is transferred to the articles brought into contact or coincidence with the path of the oscillating printing surface by the work carrying member B. It will also be clear, as the description proceeds, that suitable mechanism is provided to move the printing members D and E toward and away from the normal vibratory or oscillatory path at the end of the stroke in one direction, and at the end of the return or backward stroke. The 25 scraping members F and G are likewise moved toward and away from the path of the printing members at the time the printing members are moved out of their normal path. The movement of the printing members and the scraping 30 members out of their normal path of oscillation prevents smearing the printing after it has been transferred to the articles.

The main printing member D is arranged to move over the body, and the auxiliary printing member E is arranged to move over the neck of the bottle 34, carried in the work carrying member B. The main printing member D includes a carriage made up of two rectangular frames disposed one above the other, the upper one of 40 which is indicated at 62 and the lower one being indicated at 63. Both frames normally vibrate or oscillate simultaneously and continuously in a rectilinear path, but the upper frame that carries the main printing box to be presently described, 45 moves toward and away from the normal path of oscillation at the end of the stroke in one direction, and also at the end of the return stroke in the opposite direction. The end rail 63a of lower frame 63 has a pair of bearing ears 64. 50 Between the ears on the pin 65, secured in the ears, the sleeve bearing 66 on the inner end of connecting rod 55 is journalled. Crank shaft 48 imparts the vibratory or oscillatory movement to the main printing member D through the connecting rod 55 and the frames 63 and 62.

The side rails 63b of the lower frame 63 have laterally projecting ribs 67 which slide in channels 68 on the side beams 16, 17 of the support A and this provides for the oscillatory movement of main printing member D. The upper frame 62 of the carriage is supported on the lower frame 63 by means of four upright trip pins 69 located near the corner of the frames. The heads of these pins 69 are fixed, as by riveting, to the side rails 62a of frame 62. The shanks of these pins 69 slide in openings 70 in the side rails 63b. A trip rod 71 is slidable in a longitudinal bore 72, one in each side rail 63b, and the trip rod has a V-shaped cam notch 73 cut therein, one for each pin. The inner end of the pins 69 normally rest in the lowermost part, or trough of the cam notches 73.

The outer ends of the trip rods 71 extend free of the ends of the lower frame and on each pro- 75

jecting end there is a spring 74, one end of which bears on the frame 63, while the other end of the spring bears against nuts 75 threaded on the terminals of the trip rods. Brackets 76, one at each end of each of the trip rods 71, are bolted to the side beams 16, 17 of support A, and in each bracket is an adjustable abutment, each of which consists of a headed bolt 77, the threaded shank of which extends through openings in the bracket. The heads on the bolts are in alignment with ends of trip rods 71. The threaded shanks of bolts 77 carry nuts 78 one on each side of the bracket. By tightening the nuts, the bolt is held fast, and when they are loose the bolt may be adjusted longitudinally of the bracket.

The springs 74 normally support the trip rod 71 in the position where the inner end of cam pins 69 rest in cam notches 73. When the trip rods 71 strike the abutments embodied in the bolts 77, at either end of the stroke of the printing members, the springs 74 at the end where the striking occurs, as shown in Fig. 1, are compressed as the trip rod moves. When the trip rod moves, the cam pins 69 raise out of the cam notches 73, and the upper frame 62 moves at right angles to the normal path of oscillation. Since it will appear later that both printing members D and E move with the upper frame 62, then they are likewise moved into and out of their normal oscillatory paths by the same movement.

The rectangular printing box of the main printing member D is composed of side and end rails 79, 80 respectively, which form upstanding sides to the box for the purpose of confining the coloring material within the box. The printing box for the main printing member D is adjustable in three directions, that is, longitudinally and transversely of the machine, and also up and down. To accomplish this function, a pair of right angled arms at each end of the printing box have the legs 81 slotted at 82 to receive the shanks of bolts 83 which slide in the slots 84 in the end rails 62b of the upper frame 62. The upright legs 85 of the arms are slotted at 86 to receive the shank of bolts 87 anchored to the end rails 80. By loosening the wing nuts on the respective bolts 83 and 87, the main printing box may be adjusted, and by tightening the nuts, the boxes are secured in adjusted position on the upper frame 62.

The auxiliary printing member E includes a separate and distinct carriage member, shown particularly in Fig. 7, which imparts a differential oscillating movement to the auxiliary printing member with respect to the main printing member D. The carriage is composed of a pair of bearing blocks 88 slidable in a guide slot 89 in the one side beam 17 of support A. Secured to and extending from the outer one of blocks 88 is a pin 90 connected to the inner end of connecting rod 91, from which the auxiliary printing member E obtains its normal continuous and oscillating motion in a rectilinear path. From the inside one of the pair of blocks 88 projects a lug 91, fixed thereto in any suitable manner. A second connecting rod 92 is connected at its outer end to this lug 91 by nut 93 threaded on the rod and bearing, one on each side, against the lug. The inner end of connecting rod 92 is connected as at 94 to the confronting end of the bearing block 95 which slides in a guide channel 96 on the adjacent side rail 63a of the lower frame 63 of the carriage for the main printing member D. Connecting rod 92 extends through a slot 97 in end rail 63a of frame 63. It will thus be seen that the carriage for the

auxiliary printing member E may normally oscillate independently of, and at a differential rate of speed from the main printing member D so that a smaller printed area may be printed on the neck of a bottle at the same time a larger area is being printed on the body of the bottle.

It is necessary to provide a structure capable of moving the auxiliary printing member E toward and away from its normal path of oscillation so that the printed matter will not smear, and also to provide for printing on both the outward and return stroke. To do this, I mount a U-shaped member sidewise to slide on a pair of upright pins 98 that extend through the legs 99 of the member and across the outwardly opening channel 100 thereof. There are heads 101 on the lower ends of the pins 98 which bear against the bottom face of one leg 99 and support the member. A portion of bearing block 95 extends into the channel 100 of the member, and on this portion the shanks of the pins 98 slide up and down. There are springs 102 under the portion of the bearing block 95 that extend into the channel, encircling the pins 98, and bearing against the lower leg 99 so as to normally urge the U-shaped member downwardly. The upper end of pins 98 extend through a guide slot 103 in a bar 104 to permit longitudinal movement of the pins. The ends of bar 104 are fixed to the end rails 62b of the upper frame 62 and extend across the upper frame. There are nuts or bearing heads 105 threaded on the upper ends of the pins 98 which slide on the upper face of the bar 104. Between the lower face of the bar 104, and the upper leg 99 of the U-shaped member, there are springs 106 embracing the pins 98, which hold the U-shaped member down on the projecting portion of bearing block 95, but when the upper frame 62 is raised, as heretofore described, the bar 104 raises and moves the auxiliary printing member E with it.

The printing box of the auxiliary printing member E is rectangular in shape and smaller than the printing box for the main printing member D. The auxiliary printing box has upstanding side and end rails 107, 108 respectively to confine the coloring material within the box. The printing box for the auxiliary printing member E is adjustable transversely and longitudinally, and is also adjustable up and down on angle brackets, one at each end rail 108. One leg 109 of each bracket is slotted at 110 to receive a shank of a bolt 111 anchored in the center of each end rail 108. Nuts on the bolts 111 secure the box to the leg 109. The upright leg 112 of the brackets is slotted at 113 to receive the shank of a bolt 114 having a head 115 on the inner end thereof slidable in a channel 116 on the web 117 of the U-shaped member. Wing nuts on bolts 114 hold the brackets to the U-shaped member.

The printing surface for the printing boxes for the main printing member D and the auxiliary printing member E consists of a panel 118 one for each printing box, and this panel is secured to the lower edges of the side and end rails of the respective printing boxes. Except for size, the panels 118 are the same in both the main and auxiliary printing members D and E. The panels 118 may be made of a customary metal stencil or a regulation cloth or silk screen. The panels form the surface to support a gob of coloring material which forms the design printed on the article 34 and they are impervious to the coloring material, except for the part 119 carrying the design, and this part 119 is pervious to the

coloring material. The previous part or parts 119 permit the coloring material to pass through the panel and transfer to the article, or bottle 34, when it is brought into coincidence with the path 5 of oscillation of the printing members by the work carrying member B. The coloring material may be in powder, liquid, or plastic form customarily used in this character of printing.

In printing with my machine, the coloring material is swept back and forth over the panels 118 by the scraping members, F indicating the scraping member for the main printing member D, and G indicating the scraping member for the auxiliary printing member E. As the scraping members sweep the coloring material back and forth over the panels, a part of it passes through the previous parts 119 and is transferred to the article, or bottle 34 on the work carrying member B.

20 Each of the scraping members F and G consists of a rigid metal or wooden shoe having a shank 120 provided with slots 121. On the lower end of the shoes are flexible squeegee blades 122, preferably made of rubber, which are in wiping engagement with the panels 118, and these blades scrape and sweep the gob of coloring material over the panels. The shoes of each scraping blade have their shanks 120 adjustably connected to a cross head 123, which extends across 25 the machine. The cross head has a slot 124 extending through its thickness, and also extending across the major portion of its length, and bolts 125 in loose condition are slidable in these slots. The shanks of the bolts 125 pass through the 30 slots 121 in the shanks 120 of the shoes, and have wing nuts on their ends whereby the bolts may be tightened to hold the shoes in fixed relation to the cross head 123 for the scraping members F and G in any desired adjusted position. It will be 35 seen that the adjustment is transversely of the machine, and also up and down.

It is necessary to provide mechanism to make the scraping members step from one side to the other of the gob of coloring material at the 40 end of the outward stroke and also at the end of the inward or return stroke of the printing members so that printing may be done in both directions of the oscillating path like in my co-pending application Ser. No. 204,653, filed April 50 27, 1938. Toward this end, I provide sleeves 126 at each end of the cross head which slide up and down on the posts 127, there being one post anchored in the side beam 16, and another in side beam 17. The posts are stationary and 55 have a nut 128 on the upper end. To urge the cross head 123 normally downwardly so the blades 122 shall normally wipe against panels 118 in the main and auxiliary printing boxes a spring 129 is placed about each post with one 60 end bearing against the nut 128 and the other against the upper end of the sleeves 126. On the upper face, near each end of the side rails are pairs of cams 130, 130a respectively, the pair at one end being staggered with respect to the 65 pair at the other end. Adjacent the ends of the cross head are pairs of fingers 131, 131a mounted side by side in brackets 132 fastened to the cross head and these fingers rock in one direction, but are rigid to movement in the opposite direction. With the parts in the position 70 shown in Fig. 1, fingers 131a have raised the cross head over cams 130a, and will swing loosely in the bracket on the return stroke, at the end of which, fingers 131 are rigid when they 75 contact cams 130, and swing freely on the re-

turn stroke. This movement causes the blades 122 to step from one side and come to rest on the other side of the gob of coloring material ready to sweep the coloring material in the opposite direction when the printing members 5 D and E make the return stroke in their oscillatory path.

The work carrying member C includes a pair of disks 133 mounted concentrically on the shaft 27 in axial spaced relation. The disks turn 10 simultaneously with the shaft 27. The one disk 133, at the left, as shown in Fig. 6 is adjustable to accommodate different lengths in bottles. The hub 133a has a channel that supports half of a key 133c which slides in a keyway 133d. 15 Keyway 133d extends throughout three-quarters of the length of shaft 27 and a set screw 133b on the hub 133a bearing on the key 133c locks the said one disk in any desired adjusted position. 20

I have found it desirable to provide four article work holding stations, although any number may be used. With this in view, I provide four circular chucks 134 on one disk and four circular chucks 135 on the other disk corresponding in position to the chucks 134. Chucks 134 grip the base of the bottle 34, and chucks 135 grip the neck about the mouth thereof with the bottle axis disposed transversely across the machine. The periphery of the chucks 134 25 contact a flexible strip 136 to be presently described, to impart a rolling motion to the bottle or article held by the chucks, equal to the rate of movement of the printing member D only. That is, if the printing member D moves 12 30 inches in three seconds, the circumference of the body of the bottle 34 will move an equal distance during the same time. Chucks 134 are free to rotate on the pins 137 anchored in the adjacent disk 133. The chucks 134 have a cavity 35 138 in inner face to receive the bottom of the article such as a bottle 34, and the chucks 135 have a corresponding cavity to fit the mouth of the bottle. The face of the chucks may be shaped about the periphery of these cavities 40 45 to correct any error in timing the pick-up of the bottle, and also to center the bottle.

Chucks 135 are capable of axial movement which allows them to grip and release the neck end of the bottle 34 automatically. With this 50 in mind, I fix one end of the pins 139 to the chucks. The shanks of the pins 139 slide and rotate in openings in the corresponding disk 133 and project on the outside where a flat head 140 is formed. Between the disk 133 and the confronting face of the chucks 135 are coil springs 141, one embracing each of the four pins for the four chucks. One end of the spring bears against the disk and the other end against the corresponding chuck. Chucks 135 are normally urged inwardly by the action of the spring, but when the object or article is gripped, the heads 140 project outwardly of the outer face of the corresponding disk. 60 65

On the inside of the support A is anchored a semi-circular cam race 142 of channel-shape in cross section which has the inclination of such a pitch that the pins 139 are pulled outwardly in the position X in Fig. 12 of the drawings sufficiently to release the bottle 34, at which position the bottle is deposited on the cradle made by prongs 33 on the discharge conveyor made up of chains 25. The head 140 remains in the extended position during the rotation for another quadrant, and at the position indi- 70 75 80 85 90 95 96

cated at Y in Fig. 12 of the drawings, the head 140 slips free of the cam 142. At the point Y, a bottle 34 on the charging conveyor made up of chains 32, is in substantial alignment with the corresponding chucks 134 and 135, and when the chuck 135 snaps inwardly under the tension of spring 141, the bottle is gripped between the chucks. From the Y position in Fig. 12, the bottle is moved to the printing position Z shown in Fig. 12 of the drawings, and the relation of the bottle 34, the one printing member D, the corresponding scraping member F, and the work carrying member B in the position corresponding to the position Z, is shown in Fig. 11 of the drawings.

The work carrying member B is timed to rotate a quadrant of a revolution while the printing members D and E are raised by the trip rod 71 at each end of their oscillating path. This movement also occurs while the scraping members F and G are raised. Thus one bottle 34, is moved into the path of the oscillating printing surface, while the bottle previously printed is moved away from the path and released on the discharge conveyor 25. This timed movement is controlled by the Geneva gear C similar to that shown in my aforesaid co-pending application.

This Geneva gear comprises an inner disk 155 keyed or otherwise fixed to shaft 27, and fixed to the hub 156 of the inner disk by means of bolts 157 is the outer disk 158. Between the two disks is a third disk 159 which is free to rotate on shaft 27. The chain 51 bears on the periphery of disk 159 and the disk is rotated continuously by the chain.

Spaced equidistantly on the chain 51 in predetermined positions are a number of lugs or cams 160, which are designed to engage and swing a locking pawl 161 pivoted to leg 18 of support A at 162. The free end of pawl 161 has a bill or extension 163 that engages a notch 164 in the flange of the inner disk 155. A number of these notches 164 are provided and they are spaced equidistantly around the flange of disk 155 to correspond with the number and position of the chucks 134-135. On the side of pawl 161 is fixed a pin on which the roller 165 is mounted. The pawl 161 is normally held seated in one of the notches 164 on disk 155 by a spring 166 anchored at 167 to the leg 18 at one end and to a projection 158 on the pawl at the other end. As the chain 51 travels over the idler disk 159 the pawl is engaged in one notch 164, and the shaft 27 is locked against movement.

Extending outwardly and fixed to the chain 51 are a number of pins 169 spaced equidistantly on the chains so as not to interfere with the movement of the chain over the other sprockets about which the chain travels. Formed on the periphery of each of the inner and outer disks 155, 158 respectively, are pairs of aligned cleats 170 which are spaced equidistantly about the disks and each cleat is fashioned with a straight trailing face 170a and a round leading face 170b. The cleats 170 correspond in number and position with the chucks 134-135.

The pins 169 engage the straight faces of the corresponding pair of cleats 170, at the same time the cam 160 raises the locking pawl 161 and the shaft 27 is turned about a quadrant of a revolution. This position is shown in Fig. 8 of the drawings. When pawl 161 drops free of the cam 160, it rides on the flange of inner disk 155 until it drops into the succeeding notch 164 whereupon

the disks are locked and the shaft 27 together with work carrying member B is made stationary while the printing members D and E immediately thereafter begin another stroke. At about the same time the pawl 161 locks the disks 155-158, the pins 169 will have traveled a quadrant of a circle around the disks and are ready to drop free of the cleats 170 with which they have been engaged. To provide a certain amount of pressure to cause a whip or back lash in chain 51 to insure the pins 169 will jump free of their engaged cleats in case the pawl momentarily locks before the pins 169 are free, an arrangement is made to provide tension against the roller 52.

An intermediate part of plunger 171 slides in a sleeve bearing 172, and the bearing has ears 173 fastened to leg 18 by bolts 174. The outer end of the plunger extends outwardly of the bearing and is threaded to receive a nut 175. On the inner end of the plunger is a bearing for the spindle 176 on which the sprocket wheel 52 rotates. Between the spindle bearing and the inner end of the bearing 172 is a spring 177 which applies tension on the sprocket wheel 52, which tension may be regulated by screwing the nut 175 in or out on the end of the plunger 171.

It will be seen that I obtain compound movement in the work carrying member B. The one component is the intermittent rotary motion obtained by the Geneva gear C, which moves the articles into and away from printing position in the vibratory or oscillatory path of the printing members D and E. The other component is the rolling motion produced when the periphery of that chuck which is in printing position, engages the friction strip 136 causing the article to rotate at the same rate of speed as the main printing member D.

The endless chain 51 is rotated continuously by the sprocket 50, and the chain passes over Geneva gear C, the tension sprocket 52, and the sprocket 39. When neither of the pins 169 nor the cam 160 are engaged, the chain 51 travels about the center disk 159 which idles on the shaft 27. While this phase of operation is occurring, the printing members D and E are performing the printing operation. At the same time, pawl 161 is engaged in one of the notches 164 in the disk 155, and the disks 133 are stationary, while the one chuck 134 that is in printing position is being turned by engagement with the friction strip 136 at the same rate of speed at which the printing panel 118 on the main printing frame D is wiping over the body of the bottle that is in printing position. At the same time the panel 118 on the auxiliary printing member E is wiping over the neck of the same bottle, at a slower rate of speed than the panel 118 on the main printing member D, since there is a smaller area to print on the neck than there is on the body. The differential movement between the main and auxiliary printing members is produced by the difference in throw of the cranks 53 and 57 respectively, and the manner of translating this difference to the respective members as has been explained.

When the printing members D and E reach the end of the stroke in one direction, and they are, together with the scraping members F and G respectively beginning to raise from their normal rectilinear path of oscillation for the printing members and the normal rest position in the same path for the scraping members, which paths coincide with the surface of the article being printed; then the one pair of pins 169 on chain 51 engages the corresponding pair of cleats 170.

- on the disks 155 and 158, and the corresponding cam 160 lifts the pawl 161, all of which results in simultaneous release of shaft 27 and the turning thereof for about a quarter of a revolution.
- 5 The turning of the shaft a quarter turn moves one bottle away from the printing position and places the succeeding bottle in printing position while the printing members and scraping members are in the raised position.
- 10 During the time interval the pins 169 have traveled over a quadrant of the disks 155-158-159 that form the Geneva gear C, the printing members shall have been raised from their printing position. At the moment the pins 169 free
- 15 themselves from the cleats 170, the pawl 161 drops into the succeeding notch 164 in disk 155, and this action locks the work carrying member B with the one bottle 134 in printing position. At the same time, both printing members D and
- 20 E and the scraping members F and G drop or return from their raised positions to their normal positions and continue on the printing stroke in the opposite direction ready to go through the sequence of steps just described at the end of the
- 25 stroke.

It is necessary to adjust strip 136 to accommodate the adjustment of the one chuck 133 transversely of the machine. The strip 136 is fixed to the lower edge of a wooden plate 144 and the plate is secured to a block 145 by a pair of spaced bolts 146, the heads of which are anchored in the block. The threaded ends of the bolts extend through corresponding slots 147 in the plate 144 and have a nut 148 on the threaded end which grips the plate and holds it fast in the tightened relation. The block 145 is made of wood and is secured to the bottom bar 149 by means of a pair of bolts 150, the heads of which are anchored, one near each end of the bottom bars 149. The shanks of the bolts 150 extend through the block 145, and the threaded upper ends pass through openings in the top bar 151 and have knurled nuts 152 on the projecting ends. The bar 151 has a clamping jaw 153 which extends laterally of the bar and seats in a groove 154 in side rail 63b of the lower frame 63. The lower bar is likewise formed with a clamping jaw 149a which seats in a groove corresponding with groove 154. It will thus be seen that by

40 loosening nuts 152 the bars 151 and 149 together with block 145 may be moved transversely of the machine in any desired position within the limits of the width of the clamping jaws 153 and 149a.

45 Across one end of support A, there is secured to the end legs 19, a sheet metal skirt 190 as a protection to the operator from the throw of crank 53.

Having described my invention what I claim is:

- 60 1. A printing machine comprising a stationary support; printing members movably mounted on the support; stencils carried by the printing members for supporting coloring material having certain parts impervious and other parts pervious to the coloring material; driving means connected with the support and the printing members to impart differential oscillatory motion to the printing members with respect to one another; scraping members, one for each printing member to sweep the coloring material over the stencils
- 65 and transfer the coloring material from one face of the stencils to the other through the pervious parts; means connected with the scraping members and coacting with one of the printing members to move the scraping members toward and away from the path of the printing members;
- 70
- 75

coacting means on one printing member and the support to move the printing members toward and away from their oscillatory path at certain points; and a work carrying member movable in a path, a part of which is incident to the path of oscillation of the printing members, whereby the work is positioned to receive the transferred coloring material from the stencils.

2. A printing machine comprising a stationary support; printing members movably mounted on the support; stencils carried by the printing members for supporting coloring material having certain parts impervious and other parts pervious to the coloring material; driving means connected with the support and the printing members to impart differential oscillatory motion to the printing members with respect to one another; scraping members, one for each printing member, mounted on the support and coacting with the printing members to sweep the coloring material over the stencils and transfer the coloring material from one face of the stencils to the other through the pervious parts; means connected with the scraping members and coacting with one of the printing members to move the scraping members toward and away from the path of the printing members; coacting means on one printing member and the support to move the printing members toward and away from their oscillatory path at certain points; a work carrying member movable in a path, a part of which is incident to the path of oscillation of the printing members, whereby the work is positioned to receive the transferred coloring material from the stencils, and driving means for the work carrying member connected with the support and coacting with one printing member to impart a compound movement to the work carrying member.

3. A printing machine comprising a stationary support; printing members movably mounted on the support; stencils carried by the printing members for supporting coloring material having certain parts impervious and other parts pervious to the coloring material; driving means connected with the support and the printing members to impart differential oscillatory motion to the printing members with respect to one another; scraping members, one for each printing member, mounted on the support and coacting with the printing members to sweep the coloring material from one face of the screens to the other through the pervious parts; means connected with the scraping members and coacting with one of the printing members to move the scraping members toward and away from the path of the printing members; coacting means on one printing member and the support to move the printing members toward and away from their oscillatory path at certain points; a work carrying member movable in a path, a part of which is incident to the path of oscillation of the printing members, whereby the work is positioned to receive the transferred coloring material from the stencils, driving means for the work carrying member connected with the support and coacting with one printing member to impart a compound movement to the work carrying member, one of the components of the said compound movement of the work carrying member including an alternating rotary motion corresponding in direction with the oscillations of the printing members, and the other of said components including an intermittent rotary movement timed to operate while the printing members are positioned away from their oscillatory path.

4. A printing machine comprising a support, a plurality of printing members separately movable with respect to the support, a work carrying member movably mounted on the support for engaging an article of variable size to be printed, and separate driving means each connected to one printing member whereby said members are adapted to be moved simultaneously at different speeds over differently sized portions of said article.
5. A printing machine comprising a stationary support, work carrying means adapted to rotatably support work curved throughout its length about radii of varying lengths, a member mounted upon the support for reciprocation, a second member mounted for sliding movement upon the first member, a stencil carried by each member, and means for reciprocating each member at a different speed and with a different length of stroke whereby said stencils may print simultaneously upon differently curved portions of the work.
6. A printing machine comprising a stationary support, a printing member mounted thereon for straight line reciprocation, a trip rod movable with the member throughout a portion of its travel, means actuated by said rod moving said member angularly to its path of travel as said member approaches each travel limit, a stencil carried by said member, means reciprocating said member, and a carrier supporting work for rotation about an axis substantially at right angles to the path of travel of the printing member.
7. A printing machine comprising a stationary support, a printing member mounted thereon for straight line reciprocation, a trip rod movable with said member throughout a portion of the travel of the latter, means actuated by said rod moving said member substantially at right angles to its path of travel as the member approaches each travel limit, a second printing member slideable in the first member along a path parallel to the path of movement of the latter, a stencil carried by each member, means imparting a different length of stroke to each member, and a work carrier supporting work for rotation about an axis substantially at right angles to the paths of the printing members.
8. A printing machine comprising the combination set forth in claim 7, wherein means are provided for adjusting the length of travel of each printing member.
9. In a printing machine embodying a support, differentially oscillating printing members, a certain one of said printing members movably mounted on the support, another of said printing members movably supported on said certain printing member whereby variable areas are printed simultaneously on the same article, and means mounted on the support and coating with the printing members to urge the printing members toward and away from their path of oscillation at certain points.
10. A printing machine comprising printing members including a stencil for supporting coloring material having a certain part impervious and another part pervious to the coloring material, scraping members coating with the printing members to sweep coloring material over the stencil and transfer the coloring material from one face of the stencil to the other through the pervious part, means for moving certain of the corresponding members, means for moving one of the corresponding members at one speed, and means for moving another corresponding member at a different speed.
11. A printing machine comprising printing members including a stencil for supporting coloring material having a certain part impervious and another part pervious to the coloring material, scraping members coating with the printing members to sweep coloring material over the stencil and transfer the coloring material from one face of the stencil to the other through the pervious part, means for moving certain of the corresponding members, means for moving one of the corresponding members at one speed, and means for moving another corresponding member at a different speed, and a movable work carrying member coating with the printing members whereby the work is positioned to receive the transferred coloring material from the stencil.
12. In a printing machine, the combination of a plurality of printing members, work-carrying means for supporting an article having differently curved portions of varying radii, means for moving each printing member in a plane in tangential contact with the differently curved portions of the article, means for moving one printing member at one speed, means for moving another printing member at a different speed, and means for synchronizing the speed of the work with respect to the movement of the printing members.
13. A printing machine comprising a support, a plurality of printing members mounted for reciprocating movement on the support, a carrier for supporting work having different portions curved about radii of different lengths, means for actuating one printing member at one speed, and means for actuating another printing member at a different speed whereby different portions of the work may be printed simultaneously.
14. A printing machine comprising a support, a plurality of printing members mounted on the support for reciprocation, a carrier for supporting work having different portions curved about radii of different lengths, means for reciprocating one printing member through one length of stroke, and means for reciprocating another printing member through a different length of stroke whereby different portions of the work curved about radii of different lengths may be printed simultaneously during the movements of the printing members in either direction.
15. A printing machine comprising a support, a plurality of printing members mounted on the support for reciprocation, a carrier for supporting work of different diameters throughout the length of the work, means for reciprocating one printing member at one speed, additional means for operating one printing member at a different speed whereby portions of the work of different diameters may be printed simultaneously, and means for moving the printing members angularly to their path of travel and away from the work at both extremities of the strokes of the members.
16. A printing machine comprising the combination set forth in claim 15, wherein separate means are provided for varying the length of stroke of each printing member whereby the stroke lengths may be adjusted according to the relative lengths of the radii of the curved portion of the work to be printed.
17. A printing machine comprising a stationary support, a plurality of stencils mounted thereon for reciprocating movement, a carrier for supporting work of different diameters throughout the length of the work, means for reciprocating one printing member at one speed, additional means for operating one printing member at a different speed whereby portions of the work of different diameters may be printed simultaneously, and means for moving the printing members angularly to their path of travel and away from the work at both extremities of the strokes of the members.

its length, and means for reciprocating one of the stencils through one length of stroke, and means for reciprocating another of the stencils through a different length of stroke simultaneously with the first mentioned means whereby different sized portions of the work may be printed.

18. A printing machine comprising a work-carrying member for supporting an article curved throughout its length about radii of different lengths, stencils, means for moving one stencil through a stroke of a predetermined length, and means for moving another stencil through a stroke of a different predetermined length whereby said screens are adapted to print upon differently curved portions of said article simultaneously.

19. A printing machine comprising a carrier for rotatably supporting work curved longitudinally about radii of different lengths, stencils, reciprocating means imparting a straight line movement to one stencil, and another means imparting straight line movement to another stencil whereby said stencils are adapted to print simultaneously upon differently curved portions of said work when the stencils are traveling in either direction.

20. A printing machine comprising the combination set forth in claim 19, wherein means are reciprocated in each stencil to feed ink therethrough, each stencil being adapted to be flexed, by said means to evenly contact a portion of the work curved at right angles to the direction of travel of the stencil.

21. A printing machine comprising the combination set forth in claim 19, wherein means are provided for moving the stencils angularly to their paths and away from the work at both extremities of the strokes of the stencils.

22. A printing machine comprising the combination set forth in claim 19, wherein separated means are provided for varying the length of the stroke of each reciprocating means.

23. A printing machine comprising a stationary support, printing members mounted on the support for reciprocating movement, a shaft, cranks carried by the shaft, a rod connecting each crank to the respective printing members, means for adjusting the throw of each connecting rod, work-supporting means mounted for rotation on the stationary support, and means for actuating said shaft to reciprocate the printing members across the work to print simultaneously upon different portions of the work of different diameters.

24. A printing machine comprising the combination set forth in claim 23, wherein one printing member is mounted for sliding movement upon the other.

25. A printing machine comprising the combination set forth in claim 23, wherein means are provided for moving the printing members angularly to their path of travel and away from the work at both extremities of their respective strokes.

26. A printing machine comprising in combination, a support, a plurality of printing mem-

bers mounted for reciprocatory movement on said support, means for moving one printing member at one speed, means for moving another printing member at a different speed, each of the printing members including a surface for supporting coloring material having a certain part impervious and another part pervious to the coloring material, scraping members coacting with the printing members to sweep the coloring material over the surface to transfer the coloring material from one face of the surface to the other through the pervious part, a work carrying member intermittently movable, and rotary means actuating the work carrying member toward and away from the path of the printing members, whereby the work is positioned to receive the transferred coloring material from said surface.

27. A printing machine comprising in combination, a support, a plurality of printing members mounted for reciprocatory movement on said support, means for moving one printing member at one speed, means for moving another printing member at a different speed, each of said printing members including a surface for supporting coloring material having a certain part impervious and another part pervious to the coloring material, scraping members coacting with the printing members to sweep the coloring material over the surface and transfer the coloring material from one face of the surface to the other through the pervious part, and means for adjusting the scraping members in two different directions.

28. A printing machine comprising in combination, a support, a plurality of printing members mounted for reciprocatory movement on said support, means for moving one printing member at one speed, means for moving another printing member at a different speed, each of said printing members including a surface for supporting coloring material having a certain part impervious and another part pervious to the coloring material, scraping members coacting with the printing members to sweep the coloring material over the surface and transfer the coloring material from one face of the surface to the other through the pervious part, means for adjusting the scraping members in two different directions, and additional means for adjusting the printing members in two different directions.

29. A printing machine comprising spaced stencil screens having pervious portions through which differently colored printing materials are adapted to be forced simultaneously onto an article to be decorated, means for independently reciprocating said screens, a scraping member coacting with each of the pervious portions, means for supporting an article in rolling line contact with said screens, said screens and last mentioned means being movable relative to each other whereby the pervious portions of the screens traverse the surface of the article simultaneously.

FREDERICK SHURLEY.
